[57] CLAIM

The ornamental design for an athletic shoe sole, as shown
and described.

DESCRIPTION

FIG. 1 is a right side elevational view of an athletic shoe sole
showing our new design, the shoe upper shown in broken
lines being for illustrative purposes only and forming no part
of the claimed design;

FIG. 2 is a bottom plan view thereof;

FIG. 3 is a top plan view thereof;

FIG. 4 is a left side elevational view thereof;

FIG. 5 is a rear elevational view thereof; and,

FIG. 6 is a front elevational view thereof.
